COCKTAIL TABLE

Donald B. Gold, San Rafael, Calif., assignor to K.I.S.S.
Industries, Inc., San Rafael, Calif.

Filed Sept. 3, 1974, Ser. No. 502,602

Term of patent 14 years

Int. Cl. D6—03

U.S. Cl. D6—27

FIG. 1.

FIG. 2.

FIG. 1 is a front and top perspective view of a cocktail table embodying my new design; and

FIG. 2 is a back and bottom perspective view thereof.

I claim:

The ornamental design for a cocktail table, substantially as shown.
